(57) **CLAIM**

The ornamental design for a front cowling for a personal watercraft, as shown and described.

DESCRIPTION

FIG. 1 is a perspective view of a front cowling for a personal watercraft showing our new design, the perspective being taken from the front starboard side thereof;

FIG. 2 is an elevated side view of the front cowling for the personal watercraft of FIG. 1 taken from the port side thereof, the starboard side being a mirror image thereof;

FIG. 3 is an elevated bow view of the front cowling for the personal watercraft of FIG. 1; and,

FIG. 4 is a top plan view of the front cowling for the personal watercraft of FIG. 1.

Throughout the various figures of the drawings, certain views are not provided. The omission of a particular view is intended to convey that the element(s) depicted is/are plain and unornamented in that omitted view.

The broken line showing of environmental structure in FIGS. 1-4 is for illustrative purposes only and forms no part of the claimed design.
